Patented July 7, 1925.

Des. 67,761

UNITED STATES PATENT OFFICE.

JULIUS MILLER, OF CHELSEA, MASSACHUSETTS.

DESIGN FOR AN ICE-CREAM CONE.

Application filed March 23, 1925. Serial No. 12,839. Term of patent 3½ years.

To all whom it may concern:

Be it known that I, JULIUS MILLER, a citizen of the United States of America, residing at Chelsea, in the county of Suffolk and State of Massachusetts, have invented a new, original, and ornamental Design for an Ice-Cream Cone, of which the following is a specification, reference being had to the accompanying drawing, forming part thereof.

The figure shown is a side elevation of an ice-cream cone showing my new design.

I claim:

The ornamental design for an ice-cream cone, as shown.

In testimony whereof I affix my signature in presence of two witnesses.

JULIUS MILLER.

Witnesses:

STANLEY B. DOLLEY,
CHARLES G. VERGE.
